CLAIM

The ornamental design for a display screen or portion thereof with graphical user interface, as shown and described.

DESCRIPTION

The FIGURE is a front view of a display screen or a portion thereof with graphical user interface according to our design. The dot-dash broken line show a display screen or portion thereof and the dashed broken line showing of a graphical user interface are included for the purpose of showing portions of the article and form no part of the claimed design. The stipple-filled area shows a portion of the design that has a contrasting appearance to the non-filled areas.
